(57) **CLAIM**

The ornamental design for an insole for footwear, substantially as shown and described.

DESCRIPTION

FIG. 1 is a top, front, right side isometric view of the insole for footwear with my design;

FIG. 2 is a bottom, rear, left side isometric view thereof;

FIG. 3 is a front elevation view thereof;

FIG. 4 is a rear elevation view thereof;

FIG. 5 is an elevation view of the left side thereof;

FIG. 6 is an elevation view of the right side thereof;

FIG. 7 is a top plan view thereof;

FIG. 8 is a bottom plan view thereof; and,

FIG. 9 is a top, front, left side perspective view showing the insole for footwear in use.

The portions of a shoe shown in FIG. 9 in broken lines do not constitute part of the claimed design.

The broken line showing of a shoe is for the purpose of illustrating environment and forms no part of the claimed design.

1 Claim, 7 Drawing Sheets
